(57) **CLAIM**

The ornamental design for a housing for a test and measurement instrument, as shown and described.

DESCRIPTION

FIG. 1 is a front left perspective view of a test and measurement instrument incorporating the ornamental design of a housing for a test and measurement instrument, with feet retracted.

FIG. 2 is a front right perspective view of the housing for a test and measurement instrument of FIG. 1.

FIG. 3 is a rear right perspective view of the housing for a test and measurement instrument of FIG. 1.

FIG. 4 is a rear left perspective view of the housing for a test and measurement instrument of FIG. 1.

FIG. 5 is a front elevation view of the housing for a test and measurement instrument of FIG. 1.

FIG. 6 is a rear elevation view of the housing for a test and measurement instrument of FIG. 1.

FIG. 7 is a right-side elevation of the housing for a test and measurement instrument of FIG. 1.

FIG. 8 is a left-side elevation of the housing for a test and measurement instrument of FIG. 1.

FIG. 9 is a top plan view of the housing for a test and measurement instrument of FIG. 1.

FIG. 10 is a bottom plan view of the housing for a test and measurement instrument of FIG. 1; and,

FIG. 11 is a front right perspective view of the housing for a test and measurement instrument of FIG. 1, with feet extended.

(Continued)

The portions of the housing for a test and measurement instrument shown in broken lines form no part of the claimed design.
